UNITED STATES PATENT OFFICE.

SAMUEL ALBERTSON BUNTING, OF ASBURY PARK, NEW JERSEY.

DESIGN FOR A DIPPER.

SPECIFICATION forming part of Design No. 31,463, dated August 29, 1899.

Application filed August 2, 1899. Serial No. 725,929. Term of patent 7 years.

To all whom it may concern:

Be it known that I, SAMUEL ALBERTSON BUNTING, a citizen of the United States, residing at Asbury Park, in the county of Monmouth and State of New Jersey, have invented and produced a new and original Design for Dippers, of which the following is a specification, reference being had to the accompanying drawings, forming part thereof.

10 In the drawings forming part of this specification, Figure 1 is a side view showing my newly-designed dipper, and Fig. 2 a vertical section thereof on the line 2 2.

As shown in the drawings, the leading or 15 material feature of my design consists in a dipper A, which is cylindrical in form and open at the top, as shown at C, and closed at the bottom, as shown at D, and provided with

an annular projecting flange or rim E at the bottom thereof and with a handle F, which projects upwardly, as clearly shown in the drawings.

Having fully described my invention, I claim as new and desire to secure by Letters Patent—

The design for a dipper herein shown and described.

In testimony that I claim the foregoing as my invention I have signed my name, in presence of the subscribing witnesses, this 25th day of July, 1899.

SAMUEL ALBERTSON BUNTING.
